UNITED STATES PATENT OFFICE.

JOHN PRIMROSE, OF RICHMOND, NEW YORK, ASSIGNOR TO FOSTER WHEELER CORPORATION, OF NEW YORK, N. Y., A CORPORATION OF NEW YORK.

VAPOR CONDENSER.

Application filed March 21, 1925. Serial No. 17,181.

The general object of this invention is to provide a condenser of large capacity per unit of space occupied, high efficiency and requiring a relatively small amount of floor space, and especially adapted for use in condensing oil vapors in oil refining operations.

More specific objects of the invention are to provide an improved disposition of the condensing and heat dissipating surfaces, and to provide for a desirable control of the flow of air as the cooling fluid, over the heat dissipating surface of the condenser.

The various features of novelty, which characterize my invention are pointed out with particularity in the claims annexed to and forming a part of this specification; but for a better understanding of the invention, however, its advantages and specific objects attained with its use, reference should be had to the accompanying drawings and descriptive matter in which I have illustrated and described preferred embodiments of this invention.

25 Of the drawings:

Fig. 1 is a vertical longitudinal section through the condenser with a portion of an enclosing side wall broken away;

Fig. 2 is a transverse sectional view 30 through the condenser; and

Fig. 3 is an elevation partly in section of one of the U-shaped tube elements employed.

In the drawings, A represents the vertical side walls, and A' the vertical end walls of 35 the housing of the condenser. The upper end of the housing is closed by a top member A². This top member A² supports a fan A³, which draws air upward through the condenser to cool the vapor in the elements C which are supported within the condenser.

Supported by the side walls A and extending transversely thereto are four superposed rows of horizontal U-tube elements C, which 45 carry the vapor to be condensed. To increase the cooling of the vapor inside the elements, I surround the elements by cast iron rings C⁴ of corrugated external contour. In the construction shown, cast iron rings are 50 placed only on the upper legs of the elements to prevent the too rapid cooling of the vapor which might result from placing the rings on both the upper and lower legs.

The open ends of the upper legs C' of each

horizontal row of U-tubes C are connected 55 into a corresponding horizontal header D', and the open ends of the legs C² of the same U-tubes C are connected into a corresponding horizontal header D² below the header D'. By making the tubes C of U-shape, and 60 connecting the ends of the tube legs C' and C² into the headers D' and D², respectively, the tube legs C' and C² can expand and contract under the influence of varying temperatures without loosening the connections 65 between the headers and the legs of the tubes. As shown, in Fig. 2, the various headers D' and D² are parallel to the side wall A, and lie at the outside of the same. At each of its ends the uppermost header 70 D' is connected to a supply pipe D³⁰ through which the hot oil vapor is conducted into the condenser. The oil vapor entering the uppermost header D' through extensions D³⁰ passes from this uppermost header D' into 75 the upper legs of the U-tubes C of the uppermost row, and this vapor and any condensate formed, passes from the lower legs C² of the tube into the corresponding header D².

The above described course of the oil 80 vapor through the U-tubes of the uppermost row results in the reduction of the temperature of the oil vapor below the boiling point of a high boiling point constituent such, for example, as kerosene, causing the condensation of that constituent out of the oil vapor by reason of the cooling effect of air drawn in by the fan A³ contacting the exterior of such U-tubes. From each end of the header D² the oil vapor is conducted to the next 85 lower header D³ by means of a pair of pipe fittings D⁴. The pipe fitting D⁴ has an elbow extension D⁵, closed by a valve D⁶, which permits the draining off of the kerosene or other constituent which has been 90 condensed and collects in the elbow extension D⁵.

The vapor partially cooled by passing 95 through the upper row of U-tubes, enters the header D³ through pipe fittings D⁴ at each end of the header D³. The vapor then continues its course from header D³ through the U-tubes of the second highest row to header D⁷. In passing through this second highest row of U-tubes, the vapor is further 100 cooled and another oil product, for example, gasoline, is condensed out. This condensate is collected in the elbow extensions at the 105

bottom of the pipe fittings D^8 , which connect the second and third rows of U-tubes, similar to pipe fittings D^4 which connect the first and second rows of U-tubes. Likewise a draw-off valve can be placed in pipe fitting D^8 similar to draw-off valve D^6 , by which the condensation can be removed from pipe fitting D^8 .

The vapor passes successively through the 10 headers and U-tubes and pipe fittings of each succeeding row of U-tubes, and the vapor becomes further cooled. Each pipe fitting has a draw-off valve similar to draw-off valve D^6 , by which the oil products, for 15 example, kerosene, gasoline, naptha, and benzine, condensed at successively lower levels, are drained off. As the vapor passes down through each succeeding row of U-tubes, portions of the vapor condense in the 20 first and second rows of U-tubes as above described. That portion of the vapor, which enters the condenser through the uppermost header D' and is not condensed within either the first or second rows, is nevertheless 25 cooled and enters the third row of tubes with its volume reduced by reason of being cooled. In order to compensate for this reduction in volume of the vapor, I introduce cores C^5 into the two lowermost rows of 30 tubes. These cores C^5 are centrally supported within the legs of the U-tubes by means of outwardly projecting lugs C^6 . By the provision of these cores, I am enabled to avoid objectional reduction in velocity 35 of the vapor in the lower rows of U-tube condenser elements. If desired, cores may also be inserted in the row which is second from the top. The size of these cores and the number of them can be varied in accordance 40 with the quantity of the vapor to be condensed and in accordance with other conditions existing in any particular case.

Air channels or flues are formed by partition walls B' and B^2 supported by horizontal beams B , secured at their ends to the side walls A . These air channels or flues comprise a main central flue A^4 , and two auxiliary flues A^5 and A^6 , one at each side of the main central flue A^4 . The main 50 central flue has the vapor carrying U-tubes located therein and provides a large chamber through which air is drawn in contact with the U-tubes. Spaced openings B^3 and B^4 are cut in the partition walls forming connecting ports between the central flue A^4 and the auxiliary flues A^5 and A^6 . The two auxiliary flues provide channels through 55 which air can be drawn upwardly alongside of, independent of the main central flue, and the ports permit air to pass from the auxiliary flues into the central flue.

The bottom of each side wall A is provided with a row of holes E for the entrance of atmospheric air drawn into the condenser by the fan A^2 . More or less of

the air entering the condenser through holes E moves upwardly through the main central chamber, while the balance of the air entering through holes E is drawn upwardly through the auxiliary side channels or flues 70 A^5 and A^6 formed by the partition members B' and B^2 with the end walls A' .

Between each two rows of U-tubes, there is a row of dampers F . Each row of dampers may be opened and closed by suitable control means F' so as to vary the cooling of the vapor by varying the amount of air passing through the dampers to contact the U-tubes.

A side damper F^2 is arranged in each side channel in the same horizontal line with each main row of dampers F and each side damper has a handle F^3 by which it can be opened or closed, independent of the main row of dampers. These side dampers F^2 80 control the passage of the air upwardly through auxiliary air channels A^5 and A^6 . The openings B^3 and B^4 cut in partition walls B' and B^2 permit air in the side chambers A^5 and A^6 to pass into the main central chamber A^4 . By closing more or less the dampers F^2 , the free passage of the air upwardly through the air chambers A^5 and A^6 90 will be more or less obstructed, and more or less of this air will be diverted from the auxiliary air chambers A^5 and A^6 through the openings B^3 and B^4 into the main central chamber A^4 .

Since each main row of dampers is separately controlled, it is possible to adjust them so as to permit only the desired quantity of air to come in contact with each of the rows of U-tubes. Furthermore, since each of the side dampers is separately controlled, it is possible to adjust them so as to divert only the desired quantity of cool air from the auxiliary flues A^5 and A^6 100 through the partition ports B^3 and B^4 .

Thus, my arrangement of separately controlled dampers, increases the efficiency 110 of the condenser by permitting only the desired quantity of air to come into contact with each row of vapor carrying U-tubes and thus cool the vapor to the desired extent.

My arrangement of separate drains and draw-off valves for each pair of headers permits the fractional condensation of the oil vapor and the separation and draining 120 off of the petroleum products such as kerosene, gasoline, naptha, benzine, etc. at successively lower levels of the condenser.

While in accordance with the provisions of the statutes, I have illustrated and described the best form of embodiment of my invention now known to me, it will be apparent to those skilled in the art that changes may be made in the form of the apparatus disclosed without departing 125 from the spirit of my invention as set forth 130

in the appended claims, and that in some cases certain features of my invention may be used to advantage without a corresponding use of other features.

5 Having now described my invention, what I claim as new and desire to secure by Letters Patent is:

1. In an air cooled heat exchanger, the combination with a bank of tubular elements, of a casing enclosing said elements and having an air inlet and an air outlet between which said elements are interposed, a conduit alongside said casing in communication therewith at distributed points along 10 the length of the path of flow between said inlet and outlet, dampers in said casing and in said conduit whereby the distribution of air flow over the elements and through the conduit between said inlet and said outlet 15 may be varied.

2. In an air cooled heat exchanger, the combination with a bank of tubular elements arranged in spaced apart rows, of a casing enclosing said elements and having 20 an air inlet and an air outlet between which said elements are interposed, a conduit alongside said casing and communicating therewith by ports located at distributed points along the length of the path of flow between 25 said inlet and outlet, dampers in said casing and in said conduit above said ports, whereby by the distribution of air flow over the elements and through the conduit between said inlet and said outlet may be varied.

3. An air cooled heat exchanger, the combination with a casing having an air inlet and an air outlet and a bank of tubular elements arranged in spaced apart rows extending across the casing between said inlet 30 and outlet, a series of dampers extending across said casing between adjacent rows of said elements adapted to throttle and distribute the air flowing past the dampers to said outlet, a conduit alongside said casing and communicating with the latter at

points at opposite sides of said dampers and a damper in said conduit between said points.

4. In an air cooled heat exchanger, a box-like casing having an air inlet at its lower end and an air outlet at its upper end, a bank of horizontally disposed tubular elements arranged in horizontal rows extending across said casing, sets of dampers located at successively higher levels in said casing, each set comprising a plurality of dampers arranged between adjacent upper and lower rows of said elements and adapted to throttle and horizontally distribute the flow of air upward past the dampers over the elements above the latter, a vertical conduit alongside said casing and communicating with the latter at levels above, below and between said sets of dampers, and dampers in said conduit between said levels.

5. In a vapor condenser, the combination with a plurality of rows of U-tubes having upper and lower legs, an upper header connected to the upper legs of each row of U-tubes, a lower header connected to the lower legs of each row of U-tubes, a connection between the lower header of each upper row of tubes and the upper header of the next lower row, and a condensate draw-off connection to each of the first mentioned connections.

6. In a vapor condenser, the combination with superposed rows of U-tubes having upper and lower legs, of a casing inclosing said tubes and directing the flow of fluid 40 across said rows of tubes, connections between the lower legs of each upper row and the upper legs of the next lower row, and elongated central cores in tubes in the lower of said rows to increase the flow velocity of 45 the vapor.

Signed at New York city, in the county of New York, and State of New York, this 17th day of March, A. D. 1925.

JOHN PRIMROSE.
